(57) **CLAIM**

The ornamental design for a flexible container, as shown and described.

DESCRIPTION

FIG. 1 is an upper front perspective view of a flexible container in an open configuration in accordance with the present invention;

FIG. 2 is an upper back perspective view of the flexible container shown in FIG. 1 in the open configuration;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top view thereof;

FIG. 8 is a bottom view thereof;

FIG. 9 is an upper front perspective view of the flexible container shown in FIG. 1 in a sealed configuration; and,

FIG. 10 is an upper back perspective view of the flexible container shown in FIG. 1 in the sealed configuration.
